[57] ABSTRACT

A liquid discharging or charging device comprises means for supplying discharging or charging liquid to the surface of a photosensitive medium in an electro-photographic copying apparatus. Means is provided to apply a reference potential to the supplied liquid. A blade bears against the surface of the photosensitive medium to remove the supplied discharging or charging liquid therefrom. Means is provided to supply lubricant liquid to the area of contact of the blade with the surface of the photosensitive medium. A container is provided for collecting therein the discharging or charging liquid removed by the blade.

LIQUID DISCHARGING OR CHARGING DEVICE

BACKGROUND OF THE INVENTION

1. Field of the Invention

The invention relates to a liquid discharging or charging device. More particularly, it relates to a liquid discharging or charging device of the type in which non-insulative liquid at a desired potential is used to discharge or charge the surface of a photosensitive medium in an electrophotographic copying apparatus, and to improvements in such device so as to reduce the friction produced between the surface of the photosensitive medium and a resilient blade when the liquid used for the discharging or charging is removed from said surface by said resilient blade.

2. Description of the Prior Art

The present Applicants have previously proposed an improved electrophotographic method in Japanese Patent Application No. 1482/1972. Such electrophotographic method has comprised using a photosensitive medium basically consisting of an insulative layer, a photoconductive layer and a conductive backing member; pre-charging the surface of the insulative surface of the photosensitive medium with a desired polarity by means of an electrode, a corona discharger or a liquid discharging or charging device, said polarity being positive or negative in dependence of N- or P-type photoconductivity of said photoconductive layer, thereby forming a charge opposite in polarity to the charge of the surface of said insulative layer in the vicinity of the interface between the photoconductive layer and the insulative layer; then contacting the liquid with the charged surface of said insulative layer, said liquid being preset to satisfy the relation that $\phi \leq t/Ci \cdot d$, where ϕ is the resistivity of said liquid, Ci the electrostatic capacity of said insulative layer, d the thickness of the layer of the liquid and t the discharging or charging time, said liquid being brought to a desired potential (including a grounded potential), and simultaneously therewith or immediately thereafter, applying an image light to the surface of said photosensitive medium to thereby vary the charged condition of the photosensitive medium in accordance with the light-and-dark pattern of an original image; subsequently removing the discharging or charging liquid; thereafter uniformly exposing the entire surface of the insulative layer to light to liberate the charge in the vicinity of an interface between the photoconductive layer and the insulative layer corresponding to the dark area of the original image, thereby forming an electrostatic copy image of high contrast on the surface of the photosensitive medium. Further, the formed electrostatic image is liquid- or dry-developed by a developer chiefly composed of charged toner particles, whereafter the now visible image is transferred to paper or the like transfer medium by utilizing an internal or external field and, then, the transfer image is heated and fixed by an infrared ray lamp or like means to provide an electrophotographic copy image. On the other hand, after the image has been transferred, the surface of the aforesaid insulative layer is cleaned to remove any residual charged particles therefrom so that the photosensitive medium is ready for repeated use. Where a photosensitive medium in use comprises three layers, i.e. an insulative layer, a photoconductive layer and an insulative layer, or further includes a conductive layer, a discharging or

charging liquid is used for said discharging or charging simultaneously with or immediately before the application of image light, the liquid being at a desired potential (including a grounded potential) and preset to satisfy the relation that $\phi \leq t(C1 + C2)/C1 \cdot C2 \cdot d$, where

5 ϕ is the resistivity of the liquid, $C1$ and $C2$ the electrostatic capacities of said insulative layers, d the thickness of the layer of the liquid, and t the discharging or charging time, whereafter the subsequent steps similar to 10 those described above may occur.

In such electrophotographic method, a liquid discharging or charging device is provided so that discharging or charging liquid at a desired potential is caused to exist on the surface of the photosensitive medium to thereby effect the discharging or charging action, whereafter the liquid remaining on such surface is removed by a blade or the like means disposed in contact with said surface. Such liquid discharging or charging device has suffered from a problem that the 15 liquid used for the discharging or charging is so poor in wettability with respect to the surface of the photosensitive medium or of the resilient blade that the liquid, which is to be removed by the blade, would not readily come into the area of contact between the blade and the photosensitive medium, thus resulting in their unsmooth relative movement. In other words, the blade would tend to take off the surface of the photosensitive medium or produce noises or vibrations, thus making the setting of the blade quite difficult.

With such liquid discharging or charging device, it has also been unavoidable that when the discharging or charging is being carried out with the discharging or charging liquid supplied into the clearance between the photosensitive medium and an adjacent member for the application of image light (the entire face of an optical fiber tube if such tube is used for the application of image light simultaneously with the discharging or charging), foreign materials such as fine particles of metal, dirt, dust, fiber, etc. suspended within the copying apparatus and fine particles of toner remaining on the surface of the photosensitive medium come to mingle to the liquid. Entry of such a mixture of liquid and foreign materials into said clearance has injured or damaged the surface of the photosensitive medium and/or the face of the adjacent member (optical fiber tube). Further, during the simultaneous application of image light and discharging or charging, the clearance between the photosensitive medium and the adjacent member (optical fiber tube) must be of the order of 0 to 100 microns, which is wide enough to permit intrusion of said foreign materials into such clearance, and this has not only imparted injuries to the surfaces of the photosensitive medium and adjacent member (optical fiber tube) but also caused formation of stained copy images because those foreign materials are projected together upon the surface of the photosensitive medium during the image light application effected through the adjacent member (optical fiber tube).

60 After the surface of the photosensitive medium has been discharged or charged, the liquid used therefor must be removed by the blade, but the use of such blade alone might leave uncleared portions on the surface of the photosensitive medium because of the presence of solid toner and dust or other foreign particles sticking to such portions, or such foreign materials themselves would contact an electrostatic latent image to partly disturb such image or injure the photosensi-

tive medium or the blade. Also, it has been possible that the liquid leaks down from the opposite sides of the blade to adversely affect the subsequent steps such as overall exposure, development, etc.

SUMMARY OF THE INVENTION

It is a primary object of the present invention to provide an improved liquid discharging or charging device which completely removes discharging or charging liquid from the surface of a photosensitive medium after the liquid discharging or charging has been completed.

It is another object of the present invention to provide an improved liquid discharging or charging device which supplies lubricant liquid between a blade and the photosensitive medium when discharging or charging liquid is removed by the blade after completion of the liquid discharging or charging, thereby providing a smooth relative movement between the blade and the photosensitive medium.

It is still another object of the present invention to provide an improved liquid discharging or charging device which remove fine particles of foreign materials that have intruded into the discharging or charging liquid supplied to the device.

It is yet another object of the present invention to provide an improved liquid discharging or charging device which removes by sucking the discharging or charging liquid as it is wiped off the surface of the photosensitive medium by the blade after completion of the discharging or charging.

It is yet still another object of the present invention to provide an improved liquid discharging or charging device which employs a discharging or charging liquid having a refractive index of 1.3 or higher, thereby improving transmission of light information from an optical fiber plate to the surface of the photosensitive medium.

To achieve these objects, in accordance with the present invention a slight amount of highly lubricant liquid is supplied to the area of contact between the surface of the photosensitive medium and the resilient blade to reduce the frictional coefficient therebetween and thereby ensure the blade to maintain a stable position for removing the discharging or charging liquid. Such highly lubricant liquid may desirably have a good wettability with respect to the surface of the photosensitive medium and of the blade, but may or may not have solubility to the discharging or charging liquid. Particularly, where the wet type development is employed, the lubricant liquid should be insulative and desirably have no property which would affect the developing liquid if mingled with the latter.

As to the fine particles of foreign materials that have already intruded into the discharging or charging liquid, only the portion of the liquid which contains such foreign materials may be flushed and removed to prevent such foreign materials from intruding into the clearance between the surface of the photosensitive medium and the adjacent member before discharging or charging liquid is supplied into such clearance. Alternatively, the liquid mingled with foreign materials may be sucked for removal with a portion of the liquid before it enters into the clearance. Further, any fine particles of foreign materials which tend to intrude into the space between the photosensitive medium and the blade may be sucked for removal by a suction nozzle

provided near the area of contact between the blade and the photosensitive medium and, moreover, the liquid itself may be flowed down from the opposite sides of the blade to prevent intrusion of the foreign materials.

BRIEF DESCRIPTION OF THE DRAWINGS

The invention will become more fully apparent from the following detailed description of various embodiments thereof taken in conjunction with the accompanying drawings, in which:

FIG. 1 schematically illustrates an electrophotographic copying apparatus which incorporates an embodiment of a liquid discharging or charging device according to the present invention;

FIGS. 2 to 10 schematically illustrate various embodiments of a liquid discharging or charging device according to the present invention;

FIG. 11 is a schematic illustration of an electrophotographic copying apparatus which incorporates an embodiment of a liquid discharging or charging device according to the present invention;

FIGS. 12 to 15 schematically illustrate further embodiments of a liquid discharging or charging device according to the present invention;

FIG. 16 shows various forms of the suction nozzle shown in FIG. 15; and

FIGS. 17 to 21 schematically illustrate further embodiments of the discharging or charging device according to the present invention.

DESCRIPTION OF THE PREFERRED EMBODIMENTS

Referring to FIG. 1, a photosensitive medium (drum) 35 basically comprising an insulative layer, a photoconductive layer and a conductive backing layer is generally designated by reference numeral 1 and rotatable in the direction of an arrow. The outermost surface of the photosensitive drum may be uniformly charged by a primary charger 2. Thereafter, the said surface of the drum may be exposed to an image light through an optical fiber tube 3 while discharging or charging liquid from a tank 4 may be supplied by a supply pump 5 into the clearance between the optical fiber tube and the photosensitive drum through a supply pipe 6 so as to form a layer of liquid 7 to which an appropriate potential may be applied, thus accomplishing the simultaneous application of image light and discharging or charging. The amount of the liquid once used for the simultaneous application of image light and discharging or charging may be removed from the surface of the photosensitive drum by means of a doctor blade 8, whereupon, in accordance with the present invention, a slight amount of lubricant liquid (which may also be insulative if required) may be supplied from a tank 9 through a supply nozzle 10 to the area of contact between the doctor blade and the surface of the photosensitive drum, thereby providing smooth relative movement between the drum surface and the doctor blade. Application of the voltage to the layer 7 of the discharging or charging liquid may be done with the front face of the optical fiber tube covered with a conductive covering, as shown, or with the liquid removing doctor blade pre-treated for conductivity, or with an electrode additionally provided. After the simultaneous application of image light and discharging or charging has been done, the photosensitive drum may undergo

an overall exposure at overall exposure means 11 to provide thereon an electrostatic latent image of high contrast, which may then be developed at liquid developing means 12. The development may alternatively be done by dry type developing liquid squeezing corona discharger 13 for removal into the developing means. Thereafter, a transfer medium P may be separated from a stock pile on a transfer medium supply table 14 by a separator roll 15 and fed through a guide plate 16, a set of transport rolls 17 and a guide plate 18 to a transfer station T, where the developed image on the photosensitive drum surface may be transferred to the transfer medium by an image transfer corona discharger 19. After the image transfer, the transfer medium P may be transported through a guide plate 20, a set of transport rolls 21 and a guide plate 22 into heating-fixing means 23, where the transfer image may be fixed. The image fixing may alternatively be accomplished by any other suitable technique such as pressure-fixing, drying-fixing or the like.

After the image transfer, the photosensitive drum may be cleaned for reuse by a cleaning blade 24.

FIG. 2 shows, in perspective view, another embodiment of the liquid discharging or charging device according to the present invention. In the figure, a photosensitive medium 25 and an optical fiber plate 26 are arranged with a clearance therebetween so that the clearance may be filled with discharging or charging liquid supplied through a supply pipe 27, which liquid may then be brought to a suitable potential. The liquid once used for the discharging or charging may be removed from the surface of the photosensitive medium by means of a doctor blade 28, whereupon an amount of lubricant liquid may be supplied through a lubricant liquid supply pipe 29 to the area of contact between the blade 28 and the surface of the photosensitive medium. To permit smooth collection of the discharging or charging liquid into a receptacle 30, there is provided an air flow nozzle 31 at each side of the blade 28 so that such liquid may be directed thereby toward the center of the blade and flow down along guide grooves 28a formed therein as shown and into the receptacle 30. Where the lubricant liquid is not soluble to the discharging or charging liquid, the difference in specific gravity between the two liquids may be utilized to separate these two liquids from each other so that they can be reused for discharging or charging and lubrication, respectively.

FIG. 3 shows, in perspective view, a further embodiment of the liquid discharging or charging device according to the present invention, wherein an amount of discharging or charging liquid may be supplied into the clearance between a photosensitive medium 32 and an optical fiber tube 33 through a supply pipe 34 and then brought to a suitable potential.

Once used for its purpose, the amount of discharging or charging liquid may be removed by means of a blade 35 which is downwardly inclined with respect to the horizontal. Lubricant liquid may be supplied through a supply pipe 36 to an upper edge portion of the blade 35 so as to smooth lubrication for the area of contact between the blade and the surface of the photosensitive medium. The mixture of the discharging or charging liquid thus removed by the blade and the lubricant liquid may be forced by an air flow forming nozzle 37 to flow down the inclined surface of the blade. Obliquely downwardly of the blade 28, the mixture of the two liq-

uids may be sucked into a liquid collecting pipe 38 by a suction pump 39 and collected into a liquid receptacle 40 therebelow. Where the two liquids thus collected are insoluble to each other and have a great difference in specific gravity, they may be separated from each other due to such difference, whereafter the lighter liquid, e.g., lubricant liquid and the heavier liquid, e.g., discharging or charging liquid may be recirculated for reuse into their respective supply pipe 36 and 34 by pumps 41 and 42, respectively. A back plate 43 is attached to the blade 35 to prevent any overflow of the liquids therefrom.

FIG. 4 illustrates means for simultaneous application of image light and discharging or charging to the photosensitive medium from therebelow. In the figure, the photosensitive medium is designated by 44 and partly bathed in a pool of discharging or charging liquid within a tank 45, which liquid is at a suitable potential. The bottom wall of the tank has a portion 46 which is transparent to light so as to permit application of image light to the photosensitive medium surface through a projection lens 47 and simultaneously therewith, permit the same surface to be discharged or charged by the liquid. After the discharging or charging, the surface of the photosensitive medium may have such liquid removed therefrom by a blade 48. In the shown arrangement, the tank 45 contains therewithin an ordinary non-lubricant discharging or charging liquid and further a lubricant liquid which is soluble to the former liquid, thereby aiding in smooth operation of the blade.

Referring to FIG. 5, there is shown a further embodiment of the present invention in which an amount of discharging or charging liquid may be supplied into the clearance between a photosensitive medium 49 and an optical fiber tube 50 through a supply pipe 51 and brought to a desired potential to effect discharging or charging, whereafter the liquid may be removed by a blade 52 which is provided with a radius of curvature as shown. In this instance, lubricant liquid is only supplied to the curve 52a through a supply pipe 53 in order that such liquid may be distributed throughout the area of contact between the blade and the surface of the photosensitive medium. The blade provided with such a radius of curvature tends to experience a "take-off" phenomenon, but this can be obviated by the action of the lubricant liquid. The liquid removed by the blade and collected in a receptacle 54 is a mixture of discharging or charging liquid and lubricant liquid, but such mixture may be separated into the two liquids which in turn may be recirculated for reuse by a discharging or charging liquid pump 55 and a lubricant liquid pump 56, respectively.

FIGS. 6(a) and (b) show, in schematic view and perspective view, an embodiment of the present invention which employs a projection lens 58 as an optical system for projecting therethrough an image light upon a photosensitive medium 57 and in which discharging liquid may be supplied from a tank 59 through a supply pipe 60 to a conductive roller 61 which is at a suitable potential, so that the liquid may be applied to the surface of the photosensitive medium by the roller, thereby accomplishing simultaneous application of image light and discharging or charging. Supply means for supplying the discharging or charging liquid by such applicator system may take various forms as will hereinafter be described in connection with FIGS. 7 to 10.

Referring to FIG. 7, there is shown one form of such liquid discharging or charging device. A body of discharging or charging liquid 62 is contained within a liquid supply box 63, into which a liquid applicator member 64 formed of liquid absorbent material such as fabric, sponge, felt or the like extends and is dipped in the liquid. Because of the capillary effect of such applicator member, the discharging or charging liquid may be applied to the surface of the photosensitive medium to form a thin layer of such liquid thereon. The liquid supply box 63 may have a portion forming a keep plate member for urging the liquid applicator member against the surface of the photosensitive medium. The keep plate serves to provide a wider area of contact of the liquid applicator member with the surface of the photosensitive medium to thereby ensure stable formation of a liquid layer.

A desired voltage must be applied to the layer of discharging or charging liquid to thereby discharging or charging the surface of the photosensitive medium. The voltage application may be satisfactorily accomplished by directly short-circuiting to the liquid applicator member, or by forming a liquid removing blade 66 of a conductive material as disclosed hereinafter and short-circuiting to such blade, or by using these in combination. The discharging or charging liquid layer brought to a desired potential may take such a form on the surface of the photosensitive medium as indicated at 67 and at the same time, the image light from an original to be copied may be projected through a projection lens 68 to form on the surface of the photosensitive medium a latent image charged in accordance with the light-and-dark pattern of the original image. After this process has been completed, the discharging or charging liquid may be collected by means of a liquid removing and collecting blade 66. The blade 66 is oriented in the direction counter to the direction of movement of the photosensitive medium and biased about a pivot 69 to bear against the surface of the photosensitive medium so that the liquid can flow down the upper surface of the blade and collected in a liquid collection box 70. The blade is held by a blade holder member 71. The discharging or charging liquid collected in the liquid collection box 70 may be recirculated for reuse into the liquid supply box 63 by a pump 72, but it is imperative at this stage that such liquid be passed through a filter 73 for purification because the liquid may often contain therein admixtures such as toner particles or other foreign materials.

FIG. 8 schematically shows another embodiment of a liquid discharging or charging device according to the present invention. There is a tank 74 for discharging or charging liquid, in which is dipped a liquid absorbent member 75 formed of felt, flannel, suede, sponge or like material so that the liquid may be absorbed in the member 75 due to the capillary effect thereof and applied in a predetermined layer thickness on the surface of the photosensitive medium by means of a discharging or charging liquid applicator roller 76 formed of conductive material such as rubber of JIS 60° hardness. The liquid thus applied may be brought to a desired potential (including a grounded potential), which may be applied through the applicator roller, thereby forming a predetermined thickness of liquid layer on the area of the photosensitive surface which is exposed to an image light. In the exposure station, the exposure to an image light may be effected through a projection lens 77 si-

multaneously with the discharging or charging effected by the liquid layer.

FIG. 9 schematically illustrates still a further embodiment of the present invention. A discharging or charging liquid supply tank 78 contains therewithin a body of liquid 89 in which a supply roller 80 is dipped to absorb the liquid, so that the supply roller supplies the liquid to an applicator roller 81 which is in contact with the photosensitive medium surface so as to form a thin layer of such liquid on the surface portion of the photosensitive medium. The application of the potential to the discharging or charging liquid may be accomplished by forming the applicator roller of a conductive material and applying a desired potential thereto. The voltage may be discharged through a thin layer of liquid formed on the surface of the photosensitive medium and simultaneously therewith, an image light may be applied through a lens 82 to the photosensitive medium.

FIG. 10 schematically illustrates still another embodiment of the device according to the present invention. A tank 83 contains therewithin discharging or charging liquid, which may be delivered through a supply pipe 84 by a pump 85 and applied to the surface of the photosensitive medium through a nozzle port 86. In this instance, a great deal of developing liquid would tend to adhere to the surface of the photosensitive medium and therefore, a blade 87 for adjusting the thickness of liquid layer is provided to provide a predetermined thickness of thin liquid layer on the surface of the photosensitive medium, such liquid layer being moved to an exposure station. The adjust blade is formed of a conductive material so that any desired potential may be applied to such liquid layer through the adjust blade. Simultaneously with the discharging or charging effected by the liquid, an image light may be applied to the photosensitive medium through a lens 88.

Some desirable factors of the discharging or charging liquid formed as a thin layer in each of the above-described various embodiments will now be discussed.

1. Where ethanol of $\phi = 10^6 \Omega \text{ cm}$ is employed as the discharging or charging liquid, it is assumed that the liquid layer formed on the surface of the photosensitive medium has a thickness of 1 micron. With respect to an area of one square centimeter in such thin layer, it is assumed that the charge flows from one side *a* of the square to the opposite side *b* and thence to the earth. Then, the liquid in the thin layer has an apparent electrical resistance of $10^{10} \Omega$ which is sufficient to attain a discharging or charging effect.

2. As the liquid which is usable with the present invention, i.e. which is relatively low in electrical resistance and can be applied as a thin layer, any of the following materials has been found to be successful: methyl alcohol, ethyl alcohol, propyl alcohol, mixture of alcohol and water, mixture of propyl alcohol and kerosene, gasoline cyclohexane, mixture of water and interfacial activator, etc.

3. Where there is a requirement for a liquid which is quick to vaporize, safety means must be provided against the vaporization of such liquid and such liquid should desirably have a vapor pressure of 30 mmHg or higher. For example, methyl alcohol has a vapor pressure of 92 to 98 mmHg and is highly preferable.

4. Where a blade is required to remove the liquid, the removal would be made readier if the liquid has a lower viscosity to some extent. For example, isopropyl alcohol has a viscosity of 2.2 cp and well meets this requirement. Methyl or ethyl alcohol kerosene is also low in viscosity. Experiments have shown that viscosities up to the order of 50 cp permit ready removal of the liquid but any higher viscosity encounters difficulties. However, viscosity is not the only factor which limits the readiness of liquid removal, but the wettability of the liquid with respect to the liquid removal means is also a factor.

5. In order that a thin and uniform layer of liquid may be applied as shown in FIGS. 7 to 10, the liquid must have a good wettability with respect to the surface of the photosensitive medium. Although the surface tension does not directly represent the wettability, it seems to be much correlated with the latter. Our experiments have shown that a surface tension lower than 30 dyne/cm enables substantially uniform application of the liquid. The thickness of the liquid layer could be considerably precisely controlled to about 5 microns or less.

As has been fully described in connection with FIGS. 7 to 10, the present applicator system reduces the amount of the liquid to be supplied to the surface of the photosensitive medium during the liquid discharging or charging, thus simplifying the removal and collection of the liquid to a great extent. Further, this eliminates the possibility that the liquid once used for discharging or charging may leak to invade the overall exposure station and/or the developing station, which in turn means a very high utility of the system.

After the simultaneous application of image light and discharging or charging has been completed with a thin layer of discharging or charging liquid formed as described above, the liquid layer may be removed by a blade 89 while a lubricant liquid may be supplied through a supply pipe 90 to the area of the blade which is in contact with the surface of the photosensitive medium. The two liquids so removed may be absorbed by a liquid absorbent member 91 such as fabric, blotting paper or the like attached to the surface of the blade, and then directed downwardly into a collector 92. The two liquids collected in the collector 92 may of course be separated for reuse. In the embodiment shown in FIG. 6, alcohol was employed as the discharging or charging liquid and a layer of such liquid with a thickness of 5 microns could be formed on the surface of the photosensitive medium by means of the conductive roller 61 while kerosene as the lubricant liquid was used at the rate of about 0.1 cc per second, thus resulting in very good discharging or charging effect as well as very good liquid removal effect of the blade.

In any of the various embodiments described above in conjunction with the drawings, a success could be attained by using a lubricant liquid such as fatty hydrocarbon solvent kerosene, cyclohexane, aromatic hydrocarbon, benzene, toluene, xylene, silicone liquid, hydrocarbon chloride, hydrocarbon fluoride, or the carrier liquid for the developing solution.

As has been described hitherto with respect to a liquid discharging or charging device of the present invention, the friction between the discharging or charging liquid removing blade and the photosensitive medium may be reduced by using a lubricant liquid therebetween, thus eliminating the vibrations or "take-off"

phenomenon of the blade and facilitating the blade setting. This also eliminates the irregular removal of the said liquid resulting from the vibrations of the blade which would in turn lead to irregular formation and development of a resultant latent image. Further, the use of an insulative liquid as the lubricant liquid prevents the developing characteristic from being affected even if such liquid should enter the developing device. This effect is particularly conspicuous when the carrier liquid for the developing solution is used for the lubrication.

The use of a lubricant liquid which is insoluble to the discharging or charging liquid and greatly different in specific gravity therefrom provides easier separation of the two liquids in the receptacle to make them available for reuse.

While description has so far been made of the supply of the discharging or charging liquid to the surface of the photosensitive medium and of the removal thereof from such surface, it has been unavoidable with the described liquid discharging or charging device that foreign materials such as fine particles of metal, dust, dirt, fiber, etc. suspended within the copying apparatus and the toner particles remaining on the surface of the photosensitive medium tend to mingle with the discharging or charging liquid as it is supplied into the clearance between the surface of the photosensitive medium and the adjacent member (e.g., the entire face of an optical fiber tube is such tube is used for the simultaneous application of image light and discharging or charging) to effect the discharging or charging. Also, entry of such foreign materials into said clearance would often impart damages to the surface of the photosensitive medium and/or of the adjacent member (optical fiber tube). Further, the simultaneous application of image light and discharging or charging has involved the necessity of providing a clearance of the order of 0 to 100 microns between the surfaces of the photosensitive medium and the adjacent member (optical fiber tube), and entry of said foreign materials into such clearance would result not only in damages of the said surfaces but also contamination of the image formed on the surface of the photosensitive medium through the adjacent member (optical fiber tube) during the exposure. Therefore, it is necessary to prevent any discharging or charging liquid mingled with said foreign materials from passing into the aforesaid clearance.

In the described liquid discharging or charging device, the problem of foreign materials entering into the discharging or charging liquid might be solved by designing the entire electrophotographic copying apparatus as a highly hermetically sealed construction. In fact, however, a highly hermetically sealed construction would encounter difficulties in terms of repair of the copying apparatus and discharge of the heat produced within the apparatus, and would also involve a complex arrangement and higher cost. Moreover, it is nearly impossible to remove all the foreign particles which exist within the copying apparatus.

The present invention also provides a device for solving all the above-noted problems by employing a very simple means instead of any complex one. Briefly, this device is designed such that when discharging or charging liquid is brought into the clearance between the surfaces of the photosensitive medium and the adjacent member, only the amount of the liquid previously admixed with foreign particles may be removed so as to

prevent such foreign particles in the liquid from entering into said clearance. In other words, it is designed such that the liquid with foreign particles is sucked and removed together with a portion of the liquid before it reaches the clearance. This will more fully be described in conjunction with the drawings.

FIGS. 11(a), (b) and (c) show, in schematic view, perspective view, and side elevation, a form of the copying apparatus incorporating the present invention. A drum 89 is rotatable in the direction of the arrow and supports thereover a photosensitive medium comprising a conductive backing member (or insulative layer) 90, a photoconductive layer 91 and an insulative layer 92 closely disposed one upon another. The rotatable drum may take an alternative form such as endless belt or the like. The photosensitive medium may first be charged uniformly over the entire surface thereof by a primary charger 93, whereafter the surface of the photosensitive medium may be exposed to light information transmitted through an optical fiber tube 96 which comprises a cathode ray tube 94 provided with an optical fiber plate 95.

Simultaneously with this exposure, the surface of the photosensitive medium may be discharged or charged by the liquid discharging or charging device. The liquid discharging or charging device will now be described. The discharging or charging liquid may be supplied from a liquid reservoir and collector 97 by a pump 98 and through a liquid supply pipe 99 into the clearance between the photosensitive drum and the optical fiber plate. The supply rate of the discharging or charging liquid may be adjusted by a liquid level holding plate 100 which maintains a predetermined liquid level, as shown. Then, a suitable voltage (including a grounded potential) may be applied to the liquid 101, thus accomplishing the simultaneous application of image light and discharging or charging. The amount of the liquid used may thereafter be removed from the surface of the photosensitive medium by a doctor blade 102. Application of the suitable voltage to the discharging or charging liquid may be carried out by one of various methods, e.g., by forming the liquid level holding plate 100 of a conductive material and applying a charge thereto, or by providing a thin conductive layer on the surface of the fiber plate adjacent the photosensitive drum and applying the voltage to such layer, or by pre-treating the liquid removing doctor blade for conductivity and applying the voltage thereto, or by additionally providing an electrode for a voltage application.

In the construction of the liquid discharging or charging device described just above, foreign materials such as dust, dirt, fine particles of metal or the like suspended in the interior of the copying apparatus and the toner particles remaining on the surface of the photosensitive medium may intrude into the liquid during the discharging or charging. This may be avoided by providing a liquid flow forming nozzle 103, in addition to the liquid supply pipe, so that fresh discharging or charging liquid may be injected therethrough to cause the contaminated discharging or charging liquid to be carried away with the stream of the fresh liquid, thereby preventing entry of the contaminated liquid into the clearance between the photosensitive medium and the optical fiber plate. Reference numeral 104 designates a liquid flow forming pump.

This process will further be described with reference to FIGS. 11(b) and (c). In addition to the discharging

or charging liquid supply pipe 99, one or more liquid flow forming nozzles 103 may be provided adjacent the entrance to the clearance between the photosensitive medium and the optical fiber tube, with the nozzle ports being directed toward the opposite sides with respect to the direction of movement of the photosensitive medium in the manner as shown.

As a result, the liquid mingled with foreign materials may be removed before entering the clearance between the optical fiber tube and the photosensitive medium. The velocity at which fresh liquid is injected should desirably be higher than the velocity of the movement of the photosensitive medium relative to the optical fiber tube.

15 The contaminated liquid and the fresh liquid which has actually been used for the discharging or charging may thereafter be removed together by the blade 102 and collected in the liquid reservoir-collector 97. A filter 105 is disposed within the collector 97 to purify the 20 contaminated liquid and thereby ensure fresh liquid to be supplied therefrom to the liquid supply pipe and to the liquid flow forming nozzle or nozzles, thus enabling repeated use of the liquid. The liquid flow forming nozzle need not be separate from but may be common with 25 the liquid supply pipe, whereas this latter case is not so preferable because it often permits entry of air into the clearance between the photosensitive medium and the optical fiber tube during the simultaneous application of image light and discharging or charging to thereby 30 cause a failure of discharging or charging or disturbance to the formed image.

35 After the liquid discharging or charging, the photosensitive medium from which the discharging or charging liquid has been removed may then pass to an overall exposure process effected by an overall exposure device 107 which, if required, may have been dried by a blast drier device 106. A developing device 108 is shown to be of the wet type, but of course it may also be of the dry type using a magnetic brush or a fur brush. 40 When developed, the photosensitive medium may further be rotated to reach a squeeze charger 109, which may squeeze and remove any residual liquid remaining on the developed surface. The liquid so removed by squeezing may be either recovered for reuse in the developing device 108 or dumped away. It will be noted that the use of the dry development would involve the use of a post-charger to enhance the transfer efficiency of the developing toner. The image thus developed on the photosensitive medium may be transferred onto a 45 transfer medium 110, which has been fed to an image transfer station, by a transfer corona charger 111. The toner transferred may be fixed on the transfer medium by a fixing means 112 which may be of the heating-fixing type. After completion of the image transfer, the 50 surface of the photosensitive medium may be cleaned by a cleaning device including a cleaning blade 113, thus becoming ready for reuse. In the described manner, the information from the cathode ray tube 94 may be copied on the transfer medium.

55 FIGS. 12(a), (b) and (c) illustrate, in schematic view, perspective view, and side elevation, a further embodiment of the liquid discharging or charging device according to the present invention. Reference numeral 115 denotes a photosensitive medium movable in the direction of the arrow, 116 an optical fiber tube, and 117 a liquid level holding plate. Discharging or 60 charging liquid may be supplied into the clearance be-

tween the photosensitive medium and the optical fiber tube from a liquid reservoir and collector 118 through a liquid supply pump 119 and pipe 120. Inconveniently, such discharging or charging liquid may contain particles of some foreign materials as described previously, and in accordance with the present embodiment, this contaminated liquid may be sucked for removal by a suction pump 121 and at least one suction nozzle 122. The suction port of the liquid sucking nozzle may preferably have a diameter of 1 to 2 mm and a suction pressure of about 50 mm WG. These conditions are determined by keeping the balance with the liquid supply rate in relation to the velocity of the movement of the photosensitive medium relative to the optical fiber tube.

Further, the liquid sucking nozzle may be disposed adjacent the entrance to the clearance between the photosensitive medium and the optical fiber tube and may be movable to reciprocally scan the upper side of the clearance widthwise of the photosensitive medium, to thereby remove the contaminated liquid. In this case, the scanning velocity may be lower than the velocity of movement of the photosensitive medium. Also, the scanning may continuously occur in a reciprocal manner but alternatively, it may take place intermittently, i.e., only during the inoperative condition of the copying apparatus or except during the simultaneous application of image light and discharging or charging. The contaminated liquid thus removed by suction may be collected in the liquid reservoir-collector.

On the other hand, the liquid actually used for the discharging or charging may thereafter be removed from the surface of the photosensitive medium by a blade 123 and collected in the collector 118. The liquid thus collected through the suction nozzle as well as the liquid collected by the blade may contain therein some or less of foreign materials. Therefore, such collected liquids must be purified through a filter 124 before being reused by the liquid supply means.

FIGS. 13(a), (b) and (c) illustrate, in schematic view, perspective view and side elevation, a modification of the device shown in FIG. 12. In these figures, reference numerals 116 to 120 and 123 to 124 indicate the parts similar to those in FIG. 12.

Again in this embodiment, the discharging or charging liquid may contain therein foreign materials. In accordance with the present embodiment, however, not only such admixtures but also the residual toner or like materials remaining on the surface of the photosensitive medium may be removed. For this purpose, a foreign material wiper member 125 formed of Moltoprene (Trade Mark), rubber, fabric or any other material which would never injure the surface of the photosensitive medium may be provided at the entrance to the clearance between the photosensitive medium and the optical fiber tube and in contact with the surface of said medium so that the wiper member 125 may reciprocally scan the surface of the photosensitive medium widthwise thereof and along the upper entrance to the clearance. As a result, the foreign materials remaining on the surface of the photosensitive medium may be recovered and in addition, the liquid flow resulting from the scanning action of the wiper member may cause the contaminated liquid to flow down along the opposite sides of the optical fiber tube, thereby removing such contaminated liquid. The liquid thus used for

the discharging or charging and the liquid caused to flow down along the opposite sides of the optical fiber tube may both be collected in the liquid reservoir-collector 118. These liquids so collected may be purified for reuse through the filter 124 disposed within the collector 118.

In the specific embodiments fully described above in connection with the drawings, all the foreign materials mingled with the discharging or charging liquid can be completely removed without injuring the surfaces of the photosensitive medium and the optical fiber tube, thus providing a good discharging or charging effect. Further, the resultant image may be free of any stain which would otherwise result from the foreign particles projected upon the surface of the photosensitive medium, whereby there may be provided a copy image of very high definition.

Although the present invention relates to the liquid discharging or charging device using an optical fiber plate, consideration has heretofore been concentrated upon the discharging or charging efficiency of the discharging or charging liquid but with very little attention paid to the light-transmitting capability of such liquid. For this reason, the light information imparted from the optical fiber plate to the surface of the photosensitive medium has been diffused as it passes through the discharging or charging liquid, thus providing an extremely poor resolution. This problem of poor resolution has been particularly notable where the optical fiber plate in use is of bright NA and of large size.

When it is desired to copy the information from the optical fiber tube by the use of the discharging or charging system which employs such conductive liquid, the optical resolution provided on the surface of the photosensitive medium may be increased by bringing the fiber surface of the optical fiber tube into intimate contact with the surface of the photosensitive medium.

In the liquid discharging or charging device of the present invention, however, discharging or charging liquid must be uniformly flowed into the clearance between the surfaces of the photosensitive medium and the optical fiber plate and a greater dimension for such clearance leads to easier designing of the device, and for these reasons, the value of NA of the optical fiber plate and the refractive index of the discharging or charging liquid filling the clearance must be selected so as to permit the dimension of the clearance to be as great as possible within the range which will satisfy the required optical resolution.

Generally, information processing systems for deriving copies of light information from an optical fiber tube would find a wider use if it provides a resolution of 5 lines/mm, whereas changing the NA of the fiber to provide a sufficient resolution would encounter the inconveniences which will be described hereinafter.

For example, if the clearance between the surface of the photosensitive medium and the surface of the optical fiber plate is 100 microns and the NA of the optical fiber is changed from 0.88 to 0.55 and to 0.41, respectively, then the power of resolution will be increased by 180 percent and by 290 percent, respectively. However, the use of the fibers having such small values of NA reduces the angle of optical condensation, which in turn results in a greatly attenuated quantity of light and accordingly a greater darkness of the light information. For example, the brightness of the light information is

reduced to one-third when the NA value is reduced from 0.88 to 0.55, and to one-fiftieth when the NA value is reduced to 0.20. It is therefore impossible to simply employ a fiber of greater NA value to thereby increase the resolving power. Thus, it becomes necessary to pre-select the NA of the fiber to a great value so as to provide a sufficient quantity of light information for the surface of the photosensitive medium and moreover, to take into account the brightness of the optical fiber tube, the sensitivity of the photosensitive medium, the dimension of the clearance and the refractive index of the liquid. For example, the conditions for providing the resolving power of about 10 lines/mm will be considered below. The NA of the optical fiber commercially used in optical fiber tubes is 0.88. When such optical fiber having a core diameter of 25 microns was used in close contact with the surface of the photosensitive medium, the resolution was:

$$l/(2d) = 20 \text{ lines/mm,}$$

where d is a core diameter. When this optical fiber plate was spaced apart by 50 microns from the photosensitive surface with a discharging or charging liquid of refractive index 1.30 interposed therebetween, the resolution of the image formed on the photosensitive surface was 11 lines/mm. When the clearance was 100 microns, the resolution was 8 lines/mm.

However, when the refractive index of the liquid was 1.6, the resolution was 13 lines/mm for the clearance of 50 microns and 10 lines/mm for the clearance of 100 microns.

From this it will be seen that, when it is technically difficult to maintain the clearance below 100 microns and yet it is desired to ensure a resolution of 5 lines/mm, the liquid in use should have a refractive index higher than 1.3. Such liquid may be quinoline, mixture of eugenol and water or alcohol, mixture of Rohrbach's solution and water or alcohol, mixture of monobromonaphthalene used as immersion liquid and alcohol, or the like.

As has been fully described above, the present invention utilizes the liquid of high refractive index as the discharging or charging liquid, and this in turn permits fiber of great NA or of very high brightness to be employed to provide an excellent resolution as well as a sufficient brightness of light information.

Now, after the surface of the photosensitive medium has been discharged or charged, the liquid used therefor should be removed by a blade. The use of such blade alone, however, would produce the result that solid toner or other foreign particles such as dust and dirt are admitted between the blade and the photosensitive medium to form there build-ups of such materials which would leave areas unwashed by the liquid or which would contact the formed electrostatic latent image to disturb part of such image or injure the photosensitive medium and/or the blade. Further, the liquid might leak from the opposite sides of the blade to adversely affect the subsequent steps such as overall exposure, development, etc. To eliminate such adverse effect, improvements have been provided as shown in FIGS. 1 to 13, but the present invention also provides further efficient removal of the discharging or charging liquid and of any foreign materials present in such liquid by providing a blade and a suction nozzle adjacent the area of contact between the blade and the photosensitive medium so as to remove any foreign materials

coming into the liquid by the suction force of the nozzle and also to prevent leak of the liquid from the opposite sides of the blade.

This feature of the present invention will now be described with reference to the drawings.

FIGS. 14(a), (b) and (c) illustrate an embodiment in which the application of image light is effected by the use of a cathode ray tube (optical fiber tube) provided with an optical fiber plate while the discharging or charging is effected by a non-insulative liquid brought to a desired potential. In these figures, a photosensitive drum, designated by 126, has a photosensitive medium basically comprising an insulative layer, a photoconductive layer and a conductive layer and is rotatable in the direction of the arrow. The surface of the photosensitive drum may be uniformly charged by a primary charger 127, whereafter it is exposed to image light from an optical fiber tube 128 while a suitable voltage (including a grounded voltage) may be applied to an amount of liquid 132 supplied from a liquid reservoir-collector 129 into the clearance between the photosensitive drum and the optical fiber tube by a pump 130 and through a liquid supply pipe 131, thus accomplishing the simultaneous application of image light and discharging or charging. The liquid thus used may thereafter be removed from the surface of the photosensitive medium by a blade 133. This blade, as shown in FIG. 14(b), is inclined with respect to the axis of the photosensitive drum so that the discharging or charging liquid may flow down the blade and into a groove 134 provided along the periphery of the photosensitive drum at one end thereof.

The device of the present invention under discussion includes a suction nozzle 135 disposed so as to suck and remove the used discharging or charging liquid prior to the removal thereof by the blade 133. The suction nozzle can, in advance, suck and remove any foreign materials such as solid toner, dust, dirt and the like present in the liquid to thereby prevent these foreign materials from intervening between the blade and the photosensitive medium. The application of a desired voltage to the discharging or charging liquid may be done by providing a conductive thin layer on the surface of the fiber plate adjacent the photosensitive drum and applying the voltage thereto, or by pre-treating the liquid removing doctor blade for conductivity and applying the voltage thereto, or by additionally providing an electrode intended for a voltage application. After the discharging or charging liquid has thus been removed by the blade, the photosensitive drum surface may pass to a blast drier 136 where it is dried, and then pass through an overall exposure step at 137, followed by a development step at 138. The developing device 138 is shown to be of the wet type, whereas it will be apparent that the dry type development using a magnetic brush or a fur brush may also be employed.

The discharging or charging liquid which has flowed into the groove 134 may follow a liquid guide bar 139 projected into the groove so as to collect the liquid into the collector 129.

After the development, the photosensitive drum may have the excess developing liquid removed therefrom by a corona discharger 140, whereafter the developed image may be transferred to a transfer medium 142 by an image transfer corona discharger 141 at the transfer station. Thereafter, the surface of the photosensitive

drum may be cleaned for reuse by cleaning device such as a blade 143.

FIGS. 15(a) and (b) show embodiments in which the angularity of blade 133 is different from the that in FIG. 14. In FIG. 15(a), the blade is angularly oriented in counter relationship with the direction of movement of the photosensitive drum (indicated by the arrow), and in FIG. 15(b) it is angularly oriented in the direction coinciding with the direction of movement of the drum. The arrangement of FIG. 15(b) can arrest a greater deal of discharging or charging liquid between the blade and the photosensitive medium and therefore, by regulating the amount of the liquid so arrested and the amount of the liquid sucked through the nozzle, the receptacle 144 underlying the blade of FIG. 15(a) may be eliminated in FIG. 15(b).

FIGS. 16(a), (b) and (c) illustrate various forms of the suction nozzle 135 shown in FIG. 14 or 15. FIG. 16(a) shows a form in which the suction port is elongated, FIG. 16(b) shows a form in which a plurality of suction ports are arranged lengthwise of the nozzle and the suction force may be of a small magnitude, and FIG. 16(b') illustrates the manner in which the suction nozzle of the FIG. 16(b) is operating to suck the liquid. FIG. 16(c) shows a rod-like nozzle which is reciprocally movable to scan the blade in the direction of the arrow and remove the liquid by suction and which only requires a smaller suction force than the form of FIG. 16(b). Any of these various nozzles can sufficiently perform its function even by effecting the suction removal intermittently. The liquid thus removed may be collected for reuse in a liquid reservoir-collector, but it must of course be purified through a filter or like means disposed within the collector.

The suction effected by the above-described nozzle will now be explained more particularly.

According to the present invention, a blade and a suction nozzle are used in combination so that any foreign materials present on the surface of the photosensitive medium can be separated from such surface for suspension in the liquid between the photosensitive medium and the blade, thus being sucked for removal by the nozzle. The wind pressure required for such suction may be of the order of 50 WG, which has empirically been found to be sufficient to remove small masses of toner and fiber-like dust. The wind pressure must be increased as the photosensitive drum increases its peripheral speed, whereas a wind pressure higher than the necessary value would be more effective for the removal of the liquid but would experience more loss in the removal of the foreign materials.

The device of the present invention which has been described just above enjoys the advantages which will be described hereinafter. In accordance with this device, after the discharging or charging has been effected by non-insulative liquid, a liquid removing blade and a liquid sucking-removing nozzle are used in combination to remove all the foreign materials present in the liquid, thereby ensuring stability of the electrostatic latent image while minimizing the injuries imparted from the foreign admixtures to the photosensitive medium and/or the blade, which in turn leads to a longer service life of these members. Further, resultant copy images are always stable in general.

Means for removing the discharging or charging liquid from the surface of the photosensitive medium has been disclosed with respect to various embodiments

thereof and actually, such means can perform its intended function sufficiently, whereas there may be cases where it fails to perform the removing action completely, thus permitting a slight amount of the liquid to remain on the surface of the photosensitive medium. In an application of the present liquid discharging or charging device to the previously-described electrophotographic method, any slight amount of discharging or charging liquid remaining on the surface of the photosensitive medium during the overall exposure subsequent to the simultaneous application of image light and discharging or charging would disturb the formed image on the photosensitive medium since such residual liquid still retains its discharging capacity. Also, entry of such residual liquid into the liquid developing device would seriously affect the developing characteristic to reduce the efficiency of development.

In view of this, the present invention also provides cleaning means for use with the described liquid discharging or charging device. The cleaning means is designed such that it imparts insulative liquid to the surface of the photosensitive medium to thereby remove therefrom any slight amount of discharging or charging liquid remaining on that surface after the liquid discharging or charging process, thus completely cleaning the surface of the photosensitive medium.

FIG. 17 shows an embodiment of the electrophotographic copying apparatus which incorporates a liquid discharging or charging device of the present invention for the simultaneous application of image light and discharging and cleaning means of the present invention for completely removing any slight amount of such liquid residual on the surface of the photosensitive medium to thereby clean up such surface. In the figure, numeral 145 designates a photosensitive drum having a photosensitive medium basically comprising an insulative layer, a photoconductive layer and a conductive layer and rotatable in the direction of the arrow. The surface of the photosensitive drum may be uniformly charged with a desired polarity by a primary charger 146, whereafter it may be exposed to an image light through a lens 147 while a discharging or charging liquid supply pipe 148 may supply the clearance between a transparent plate 149 and the photosensitive medium 145 with a discharging or charging liquid 150, which is brought to a desired voltage (including a grounded voltage) thus accomplishing simultaneous application of image light and discharging. The application of the voltage to the discharging or charging liquid may be carried out by providing a conductive layer on the surface of the transparent plate 149 adjacent the photosensitive drum and applying a voltage thereto, or by pre-treating a liquid removing doctor blade 151 for conductivity and applying a voltage thereto, or by additionally providing an electrode for a voltage application. The liquid so used may then be removed from the surface of the photosensitive medium by the doctor blade 151 and collected in a liquid collector 152. If desired, the collected liquid may be recirculated for reuse into a liquid discharging or charging device 153. As described above, most of the discharging or charging liquid can be removed by the doctor blade 151 but with a slight amount of it remaining on the surface of the photosensitive medium. The present invention provides a cleaning device 154 at a subsequent station to completely remove such slight amount of discharging or

charging liquid. As shown, a cleaning liquid container 155 contains therein a body of cleaning liquid 156 which is a liquid having good wettability with respect to the surface of the photosensitive medium and presenting a high electrical resistance, and a pair of parallel rollers 157 and 158 are rotatably mounted within the container. Rotations of these rollers in the directions of respective arrows may raise the liquid to wash away the residual discharging or charging liquid from the surface of the photosensitive medium. As a result, the cleaning liquid will contain the removed discharging or charging liquid, but the two liquids may be separated from each other by a liquid separator 159 through the utilization of the difference in specific gravity between the two liquids, whereby the cleaning liquid may be reused for the cleaning purpose while the discharging or charging liquid may be collected in a collector 161 for reuse at the aforesaid liquid discharging or charging device.

The surface of the photosensitive medium thus cleaned still retains thereon an amount of cleaning liquid, which may be removed and collected by a doctor blade 162. Even after being wiped by this doctor blade, the surface of the photosensitive medium may still retain a slight amount of cleaning liquid which, however, will not affect the formed image so seriously as the residual discharging or charging liquid, because of its high electrical resistance. After so cleaned, the photosensitive medium may pass an overall exposure device 163 for overall exposure, followed by a developing step. The developing device is shown in a block 164, whereas the dry type development using a magnetic brush, a fur brush or a cascade may also be employed. After development, the photosensitive drum may pass a corona discharger 165 which removes any excess developer from the drum surface, whereafter the developed image may be transferred to a transfer medium 167 by an image transfer corona discharger 166 at the transfer station. Thereafter, the photosensitive medium may be cleaned for reuse by cleaner means such as a cleaning blade 168.

FIG. 18 illustrates another embodiment of the liquid discharging or charging device and of the cleaning device therefor. A reservoir 169 stores therein discharging or charging liquid, and a liquid absorbent member 170 extends downwardly into the liquid within the reservoir. The liquid may be absorbed by the absorbent member due to the capillary effect thereof and applied to a predetermined thickness on the surface of the photosensitive medium by a conductive applicator roller 171. The applied liquid may be brought to a desired potential (including a grounded potential) applied to the roller 171 to thereby form a predetermined thickness of liquid layer in an exposure station. In the exposure station, the image light application may occur through a projection lens 172 simultaneously with the discharging effected by the liquid layer. After the simultaneous application of image light and discharging, the discharging or charging liquid once used may be removed by a doctor blade 173 and recirculated for reuse into the discharging or charging device through a circulation pipe 175 provided with a pump 174. Any slight amount of discharging or charging liquid which could not be removed by the doctor blade 173 may be washed away by a cleaning device which will be described hereinafter. The cleaning liquid may be supplied upwardly from a cleaning liquid tank 176 through a pump 179 into a chamber 178 defined by a doctor

blade 177, thereby washing the surface of the photosensitive medium. After washing, the cleaning liquid may be recovered into the tank 176 through a pump 179', but such recovered cleaning liquid contains therein much of the discharging or charging liquid and therefore, the two liquids must be separated in a separator chamber 181 defined by a partition plate 180, utilizing the difference in specific gravity between the two liquids. When separated, the cleaning liquid and the discharging or charging liquid may be delivered for reuse to the cleaning station and the discharging or charging station, respectively.

FIG. 19 shows a further embodiment of the cleaning device. Reference numeral 182 designates a transparent plate disposed adjacent the surface of the photosensitive medium. Discharging or charging liquid may be supplied between the transparent plate and the photosensitive medium through a supply pipe 183 and a desired potential (including a grounded potential) may be applied to the liquid through an electrode or the like provided on the transparent plate, thereby accomplishing the discharging or charging while an image light may be applied to the photosensitive medium through a projection lens 184. After completion of the discharging or charging, the liquid may be removed by a doctor blade 185 and collected in a collection receptacle 186. The liquid thus collected may be recirculated by a pump 187 for reuse as discharging or charging liquid. Even after having been wiped by the doctor blade 185, the surface of the photosensitive medium may still retain thereon a slight amount of discharging or charging liquid, which may be completely washed away by a cleaning device to be disclosed. There is shown a cleaning liquid tank 188, from which cleaning liquid may be pumped out by a pump 189 and through a circulating means 190 and injected as a jet through a nozzle 191 onto the surface of the photosensitive medium, thereby washing away all the discharging or charging liquid residual on the surface of the photosensitive medium. Thereafter, the cleaning liquid may be substantially removed by a blade 192 and nearly completely removed by a packing member 193. It will be noted that means for separating the cleaning liquid and the discharging or charging liquid from each other may be provided within the cleaning liquid tank.

In any of the various embodiments described above, a good result may be obtained by using a cleaning liquid such as fatty hydrocarbon (kerosene, cyclohexane), aromatic hydrocarbon (benzole, triole), hydrocarbon chloride (carbon tetrachloride, hydrocarbon fluoride, or silicone).

When water was used as the discharging or charging liquid, the use of kerosene as the cleaning liquid resulted in a particularly good cleaning effect.

As has been fully described, the cleaning device for the liquid discharging or charging device according to the present invention can completely wash away any slight amount of discharging or charging liquid residual on the surface of the photosensitive medium after the liquid discharging or charging, thereby protecting the formed latent image against any adverse effect. Particularly, where the developing device is of the wet type, the cleaning device contributes to the production of highly clear copy images without marring the developing characteristic.

In the various embodiments shown in FIGS. 1 to 19, an image light has been provided from an original

image through either an optical fiber tube or a projection lens. The use of a projection lens for the exposure is meritorious in effecting a magnified projection but is demeritorious in that the optical system itself occupies a larger space and a light source of greater wattage is required. To overcome this, the present invention proposes to use an optical fiber plate to project an original image upon the surface of the photosensitive medium, without employing a lens. This will more fully be described with reference to FIG. 20.

FIGS. 20(a) and (b) show an embodiment in sectional view and perspective view. In the shown embodiment, the device for the simultaneous application of image light and liquid discharging or charging overlies the photosensitive drum. The photosensitive drum, designated by 194, and the optical fiber plate, designated by 195, are arranged to provide a clearance therebetween, into which discharging or charging liquid may be supplied through a supply pipe 196, and the liquid may form a liquid layer in the clearance as the photosensitive drum rotates. A desired potential (including a grounded potential) may be applied to the liquid layer through a transparent electrode 197 to thereby discharge or charge the surface of the photosensitive drum. On the other hand, the application of image light may be carried out by moving an original O between guide plates 198₁, 198₂, two sets of transport rolls 199,200 (one roll of each set being rotatably embedded in the optical fiber plate) and guide plates 202₁, 202₂, and by causing the moving original to be scanned by an exposure device 203 to thereby expose the surface of the photosensitive medium to the light passed through the original. The discharging or charging liquid, once used, may be removed from the surface of the photosensitive medium by a blade 204.

In the described embodiment, the light passed through the original is utilized for the exposure, whereas the present invention also permits the use of the light reflected by the original as shown in FIG. 21. In this figure, the photosensitive medium 205 and the optical fiber plate 206 are disposed in closely adjacent relationship so that discharging or charging liquid may be supplied into the clearance therebetween through a liquid supply pipe 207 so as to form a layer of such liquid in the clearance. A desired potential (including a grounded potential) may be applied to the liquid layer through a transparent electrode 208 to thereby discharge or charge the surface of the photosensitive medium. The liquid once used for the discharging or charging may be removed from the surface of the photosensitive medium by a blade 209. On the other hand, exposure to image light may be done in such a manner that a fiber 210, forming a part of the optical fiber plate 206 is used solely for the purpose of transmitting the light from illuminating light source means 211 to the surface of the original O and that fiber 210₂ forming another part of the optical fiber plate is used solely for the purpose of transmitting the reflected image light from the surface of the original to the surface of the photosensitive medium. Thus, the original O may be transported as it is urged into intimate contact with the optical fiber plate 206 by a pressure plate 212, thereby accomplishing the exposure of the photosensitive medium surface to the reflected image light. The original used herein may be in the form of sheet or thicker original such as book or the like.

In order to obtain a copy image of high resolution from an original image by using the above-described system, the following conditions must be satisfied; 1) good intimate contact be provided between the original and the optical fiber plate — this can be satisfied by the use of a transparent pressure plate; 2) consideration be given to the light-transmissibility and diffusion coefficient of the original to be copied — those originals used in diazo duplication are usable and the reflection system places no limitations upon the type of original; 3)

the resolution of the optical fiber plate be kept as the resolution of the formed image; 4) the clearance between the surfaces of the optical fiber plate and the photosensitive medium be as narrow as possible; and 5) the refractive index of the liquid be considered where the liquid discharging or charging system is employed — the higher the index (at least 1.3), the better.

An example of empirical data will be shown below. An optical fiber plate of NA=0.8 and resolution of 1/2d=20 lines/mm was employed with a clearance of 100 microns from the surface of the photosensitive medium, and discharging or charging liquid having a refractive index of 1.3 was used. The result was a resolution of 10 lines/mm. To further enhance the resolution in this example, use may be made of an optical fiber plate of smaller NA value, but the quantity of light will be decreased by about one-fiftieth for NA=0.2, as compared with the case of NA=0.8, and therefore the NA value must be considered in relation to the possible loss in the quantity of light.

As has been fully described above, the use of an optical fiber plate for the exposure to an original image reduces the space occupied by the optical system much more than the through-the-lens exposure system of the prior art, thus reducing the size of the entire copying apparatus. Further, the exposure to an image light occurs through the optical fiber plate in a fashion similar to the contact print, and this permits the use of a smaller wattage for a light source. Furthermore, the absence of the optical projection lens system completely prevents production of blurred copy images which would otherwise result when the optical lens is deviated from its normal place due to vibrations or the like of the copying apparatus body.

I claim:

1. A liquid discharging or charging device comprising:
means for supplying discharging or charging liquid to a surface to be discharged or charged;
means for applying a reference potential to said supplied liquid;
a blade bearing against said surface to be discharged or charged for removing said supplied discharging or charging liquid from said surface after charging or discharging said surface;
means for supplying lubricant liquid to the area of contact of said blade with said surface; and
a container for collecting therein said discharging or charging liquid removed by said blade.
2. A device according to claim 1, wherein said discharging or charging liquid is electrically conductive.
3. A device according to claim 1, wherein said reference potential is a grounded potential.
4. A device according to claim 1, wherein said lubricant liquid is electrically insulative.
5. A device according to claim 1, wherein said means for supplying said discharging or charging liquid is

means for applying said discharging or charging liquid to said surface to be discharged or charged.

6. A device according to claim 5, wherein said means for applying said discharging or charging liquid comprises an applicator roller.

7. A device according to claim 5, wherein said means for applying said discharging or charging liquid comprises a liquid absorbent slideable applicator member.

8. A device according to claim 1, wherein said means for supplying said discharging or charging liquid comprises a nozzle for injecting said liquid upon said surface to be discharged or charged, and a blade for forming said liquid applied to said surface into a predetermined thickness of layer.

9. A device according to claim 1, wherein said means for supplying said discharging or charging liquid is a container for said discharging or charging liquid in which said surface to be discharged or charged can be immersed.

10. A device according to claim 9, wherein said container for said discharging or charging liquid is common with said container for collecting the same liquid.

11. A device according to claim 9, wherein said container for said discharging or charging liquid contains therein said discharging or charging liquid and said lubricant liquid in a mixed form.

12. A device according to claim 1, wherein said discharging or charging liquid removed by said blade is recirculated for reuse into said discharging or charging liquid supply means.

13. A device according to claim 12, wherein a filter for purifying said discharging or charging liquid is provided in the path of said recirculation.

14. A device according to claim 1, wherein the portion of said blade which is in contact with said surface to be discharged or charged is provided with a curvature.

15. A device according to claim 1, wherein said blade is oriented in forward direction with respect to the direction of movement of said surface to be discharged or charged.

16. A device according to claim 1, wherein said blade is oriented in counter direction with respect to the direction of movement of said surface to be discharged or charged.

17. A device according to claim 1, wherein said discharging or charging liquid and said lubricant liquid are separated for repeated use within said container due to the difference in specific gravity therebetween.

18. A liquid discharging or charging device 8 comprising:

means for supplying discharging or charging liquid to a surface to be discharged or charged;

means for applying a reference potential to said supplied liquid;

a blade bearing against said surface to be discharged or charged for removing said supplied discharging or charging liquid from said surface after charging or discharging said surface;

means for supplying lubricant liquid to the area of contact of said blade with said surface;

means for removing said discharging or charging liquid removed by said blade; and

a container for collecting therein discharging or charging liquid removed by said blade.

19. A device according to claim 18, wherein said removing means includes means for blowing an air flow

in the direction for causing said discharging or charging liquid on said blade to flow down along said blade.

20. A device according to claim 18, wherein said removing means includes a suction nozzle provided above said blade so as to suck and remove said discharging or charging liquid on said blade.

21. A device according to claim 20, wherein said suction nozzle sucks said discharging or charging liquid as it moves over said blade.

22. A device according to claim 20, wherein said suction nozzle has a plurality of suction ports arranged along the line of contact of said blade with said surface to be discharged or charged.

23. A device according to claim 20, wherein said suction nozzle has an elongated slit-like suction port disposed along the line of contact of said blade with said surface to be discharged or charged.

24. A liquid discharging or charging device comprising:

means for supplying discharging or charging liquid to a surface to be discharged or charged;

means for applying a reference potential to said supplied liquid;

a blade bearing against said surface to be discharged or charged for removing said supplied discharging or charging liquid from said surface after charging or discharging said surface;

means for supplying lubricant liquid to the area of contact of said blade with said surface;

a container for collecting therein said discharging or charging liquid removed by said blade; and

means for imparting cleaning liquid to said surface to clean the same after said discharging or charging liquid has been removed by said blade.

25. A device according to claim 24, wherein said cleaning liquid is insulative.

26. A device according to claim 24, wherein said cleaning means includes a nozzle for injecting said cleaning liquid to said surface to be discharged or charged, and means for removing said injected cleaning liquid.

27. A device according to claim 26, wherein said means for removing said cleaning liquid is a blade bearing against said surface to be discharged or charged.

28. A device according to claim 26, wherein said means for removing said cleaning liquid is a liquid-absorbent member frictionally slideable with respect to said surface to be discharged or charged.

29. A liquid discharging or charging device comprising:

means for supplying discharging or charging liquid to the surface of a photosensitive medium;

means for applying a reference potential to said supplied liquid;

means for projecting an image light to said surface of said photosensitive medium through said discharging or charging liquid to which said reference potential is applied;

a blade bearing against said surface of said photosensitive medium for removing therefrom said supplied discharging or charging liquid after charging or discharging said surface;

means for supplying lubricant liquid to the area of contact of said blade with said surface of said photosensitive medium; and

a container for collecting therein said discharging or charging liquid removed by said blade.

30. A device according to claim 29, wherein said means for projecting an image light projects an original image through a projection lens.

31. A device according to claim 29, wherein said means for projecting an image light is an optical fiber tube disposed adjacent said surface of said photosensitive medium.

32. A device according to claim 29, wherein said means for projecting an image light comprises an optical fiber plate disposed adjacent said surface of said photosensitive medium, a passage for an original provided on that side of said plate which is remote from said photosensitive medium, and light source means for illuminating said original with said passage interposed therebetween.

33. A device according to claim 29, wherein said means for projecting an image light comprises an optical fiber plate having a fiber for transmitting original illuminating light disposed adjacent said surface of said photosensitive medium, and a fiber for transmitting light from the surface of said original to said surface of said photosensitive medium; light source means for illuminating said original; and an original supporting portion.

34. A liquid discharging or charging device comprising:

an adjacent member closely spaced apart from a surface to be discharged or charged;

means for supplying discharging or charging liquid into the clearance between said surface and said adjacent member;

means for removing foreign materials mingled with said discharging or charging liquid in the form of a mixture;

means for applying a reference potential to said sup-

plied discharging or charging liquid; a blade bearing against said surface to be discharged or charged for removing said supplied discharging or charging liquid from said surface after charging or discharging said surface;

means for supplying lubricant liquid to the area of contact of said blade with said surface; and a container for collecting therein said discharging or charging liquid removed by said blade.

35. A device according to claim 34, wherein said adjacent member is a face plate of an optical fiber tube.

36. A device according to claim 35, wherein said discharging or charging liquid has a refractive index of 1.3 or higher.

37. A device according to claim 34, wherein said means for removing foreign materials is means disposed adjacent the entrance to said clearance to flush and remove the mixture of said liquid and said foreign materials.

38. A device according to claim 37, wherein said flushing and removing means is a liquid-flow forming rod movable over the entrance to said clearance.

39. A device according to claim 34, wherein said means for removing foreign materials is suction means disposed adjacent the entrance to said clearance to suck the mixture of said liquid and said foreign materials.

40. A device according to claim 39, wherein said suction means is a suction nozzle.

41. A device according to claim 40, wherein said suction nozzle is movable over the entrance to said clearance.

UNITED STATES PATENT OFFICE
CERTIFICATE OF CORRECTION

Patent No. 3,835,355 Dated September 10, 1974

Inventor(s) SYUSEI TSUKADA

It is certified that error appears in the above-identified patent and that said Letters Patent are hereby corrected as shown below:

In the cover sheet, left-hand column, between items [21] and [52], insert:

-- [30] Foreign Application Priority Data

August 17, 1972	Japan	83847/1972
October 25, 1972	Japan	106844/1972
November 8, 1972	Japan	111845/1972
November 13, 1972	Japan	113639/1972 --

Signed and sealed this 17th day of December 1974.
